HIGH SPEED SPINDLE CONSTRUCTION

Albert H. Dall, Silverton, and Frederick S. Haas,
Cincinnati, Ohio, assignors to Cincinnati
Grinders Incorporated, Cincinnati, Ohio, a
corporation of Ohio

Application June 23, 1937, Serial No. 149,854

5 Claims. (Cl. 308—73)

This invention relates to machine tools and more particularly to an improved form of high speed spindle construction for the rotary tools thereof.

5 One of the objects of this invention is to provide means for supporting a machine tool spindle for high speed rotation.

Another object of this invention is to provide improved means for anti-frictionally supporting a spindle for high speed rotation and at the same time maintaining the plane of rotation of the cutting tool, such as a grinding wheel, in a predetermined plane within precision limits.

10 Other objects and advantages of the present invention should be readily apparent by reference to the following specification considered in conjunction with the accompanying drawings illustrative of one embodiment thereof, but it will be understood that any modifications may 15 be made in the specific structural details within the scope of the appended claims without departing from or exceeding the spirit of the invention.

15 Referring to the drawings in which like reference numerals indicate like or similar parts:

Figure 1 is a sectional view of a high speed spindle construction embodying the principles of this invention.

Figure 2 is a section on the line 2—2 of Figure 1.

Figure 3 is a section on the line 3—3 of Figure 1.

Figure 4 is a sectional view showing a modified form of the invention.

35 Figure 5 is a detail view of one of the double tapered rocker shoes shown in Figure 4.

Figure 6 is an end view of the shoe shown in Figure 5.

Figure 7 is a schematic diagram showing the 40 relationship of the angles of the double tapered shoe with respect to the axis of the spindle.

Figure 8 is an enlarged detail of one of the shoes shown in Figure 4.

Figure 9 is a detail view showing the details 45 of the thrust bearing shown in Figure 1.

In Figure 1 of the drawings, the reference numeral 10 indicates a part of the structure of a machine tool, such as a grinding machine, said structure comprising spaced walls 11 and 50 12 having aligned openings 13 and 14 respectively formed therein. A sleeve 15, having a flange portion 16 on one end, is inserted in these openings with the flange 16 abutting one side of the wall 12, and held in place by a nut 55 17 threaded on the end of the sleeve and en-

gaging the outside of the wall 11. The sleeve rests on the bottom of the openings 13 and 14 and is held against rotation by a plurality of dowel pins 18 and 19, and is prevented from lifting by means of set screws 20 and 21.

5 The sleeve 15 has aligned bores 22 and 23 formed in opposite ends thereof and a tool spindle 24, which is disposed in the sleeve, has reduced journals 25 and 26 passing through these aligned bores.

10 One end of the spindle 24 has a shoulder 27, against which an annular guard 28 is adapted to be positioned. A grinding wheel 29 is positioned on the spindle with one side in engagement with the central boss 30 of the guard 28 15 and held against rotation by a clamping screw 31 which engages an enlarged flange 32 mounted on the other side of the grinding wheel, said screw being threaded in an axial bore in the end of the spindle.

20 The grinding wheel may be provided with a trued surface 33 of precision width which is adapted to fit into and engage a recess 34 in a work piece 35 for finishing the bottom surface of said recess. Since the grinding wheel is small, 25 it must be rotated at a high rate for obtaining the desired surface speed.

25 In order to obtain the necessary speed of rotation with a minimum amount of power, a form of anti-friction bearing means is provided for 30 supporting the spindle at spaced points which will permit of high speeds of rotation. A plurality of rocker shoe bearing members 36 are provided in the bore 23 of the sleeve 15 for engagement with the journal 26 of the spindle. 35 Each of these rocker shoe members is provided with a boss 37 on the outside periphery, as shown in Figure 8, the radius of the curvature of which is less than the radius of the bore 23 whereby only line contact is made between the shoe and the bore, so that the shoe is free to pivot a limited amount. A set screw 38 is provided for holding the shoe in position circumferentially and at the same time permitting the pivoted movement. The bearing surface 39 of the shoe has 40 a beveled end so that rotation of the shaft in its prescribed direction will cause oil to be drawn in between the shoe and the journal and cause a hydrostatic pressure to be generated by the hydrodynamical condition in the oil film. The 45 variations in the pressure of the fluid will cause the shoe to rock a very limited amount about its pivot by line contact with the spindle.

The thickness of the shoe and oil film determines the position of the axis of the shaft with 55

respect to the axis of the bore 23. For set up purposes, the set screws 38 of the two lower shoes are backed off sufficiently to insure peripheral contact of the shoes 34 and 35 with the interior 5 of the bore 23, and the set screw 39' associated with the upper shoe 36 is tightened down until all of the shoes are tight between the shaft and the bore and then the set screws 38 are tightened and locked. The set screw 39' is then backed off a sufficient amount to permit free rotation of 10 the spindle.

A similar set of bearing shoes is provided in the bore 22 and by the same method of set up, it will be apparent that it is possible to align 15 the axis of the spindle parallel to the axis of bores 22 and 23.

To obtain the best results these bearings should be supplied with lubricating oil under some pressure, and to this end the sleeve 15 20 is provided with openings 41 through which oil may be introduced to the interior of the sleeve from a suitably located reservoir or from a pump. In order that a pressure may be built up within the sleeve, oil seals are provided at each end 25 of the sleeve and to accommodate these, each end of the sleeve is counterbored as at 42 and 43 to form shoulders against which the sealing members 44 and 45 may bear. These members have a running fit with the shaft and are held 30 against the shoulders by springs 46, which are held in position by cup shaped members 47, threaded into the counterbores. Since there is very little leakage past these seals, it will be apparent that a substantial pressure may be 35 built up within the sleeve to maintain the desired supply of lubricant to all of the bearing shoes so that the necessary hydrostatic pressure will be generated for supporting the spindle.

The spindle 24 is provided with a tapered portion 48 upon which is keyed a driving pulley 49. A belt 50 may be passed around this pulley for actuating the same.

It will be noted that since the rocker shoe bearing surface extends parallel to the surface 45 of the spindle, it is free to move axially, which would make the position of the grinding wheel 33 with respect to the work uncertain, and therefore means have been provided for stabilizing the axial position of the spindle. One form that 50 this means may take is shown in Figures 1 and 9, and comprises a thrust bearing 51 consisting of an inner race member 52 which is fixed with the spindle and an outer race member 53 which is held in a fixed position in the housing 54. A 55 lubricant reservoir 55 may be attached to the housing 54 and connected by a channel 56 for lubrication of the thrust bearing.

If so desired, the thrust bearing shown in Figure 1 may be eliminated and one of the rocker 60 shoe bearings altered to take the thrust and thus preserve the longitudinal position of the spindle, as well as serve as a radial bearing. This form of construction is shown in Figure 4 of the drawings, and the particular shape of the shoe 65 is illustrated in Figures 5 and 6. Each bearing shoe 57 has double conical surfaces 58 and 59, and each of these surfaces are relieved at 60 to provide inlet for the oil.

The spindle 24 is provided with double tapered 70 journals 61 and 62 and it will be noted from Figure 7 that a line of contact between the tapered journal and the spindle, and lying in a radial plane, such as the line 63, will make an acute angle 64 with the axis of the spindle. The 75 shoes 57 are provided with hardened inserts 65

having conical recesses 66 for receiving the end of locking screws 67.

There are three shoes 57 equally spaced about the periphery of the double cone journals on the spindle and the method of set up is the same as 5 that previously described in connection with the plane rocker shoes. It will now be apparent that the double cone rocker shoes are capable of preventing axial movement of the spindle in either direction by generating an hydrostatic 10 pressure which acts perpendicular to the double cone journals, and therefore at opposite acute angles to the axis of the shaft resulting in opposed axial components which prevent axial oscillation of the spindle. 15

We claim:

1. In precision high speed spindle construction, the combination with a spindle having spaced bearing portions formed thereon, of a support therefor having bearing recesses alignable with the bearing portions on the spindle, a plurality of circumferentially spaced bearing shoes circumscribing the spindle within each of said recesses, said shoes having inner portions corresponding in shape to the bearing portion 20 of the spindle engageable thereby and outer faces supportable for oscillation relative to the circumscribing wall of the bearing receiving recesses, means maintaining said shoes against axial displacement in the recesses, means coupled 25 with said recesses for maintaining the same filled with lubricant under appreciable hydrostatic pressure whereby upon rotation of the spindle wedge-like oil films will be produced intermediate the shoes and bearing portions of the spindle, 30 maintaining the spindle in fixed axial position under varying load conditions, certain of said shoes having inner faces reacting in a direct radial direction against the bearing portions of the spindle for retaining the same against radial movement and other of said shoes, each having individual angularly related portions creating force components reacting against the spindle in opposite balanced angular directions 35 in a radial plane whereby to restrain the spindle against longitudinal movement as well as radial displacement of its axis of rotation. 40

2. In precision high speed spindle construction, the combination with a spindle adapted to be rotated at high speed, of means for supporting the spindle including a supporting element providing closed bearing receiving chambers, groups of bearing elements disposed along the chambers in circumscribing relation to the spindle, said elements being mounted for limited oscillatory 45 movement with respect to the spindle whereby to create wedge-like oil films during rotation of the spindle, restraining the spindle against radial displacement, certain of said elements having portions disposed in non-parallel relation with 50 respect to the axis of the spindle, the spindle having corresponding, non-parallel zones of general frusto-conical type opposing the faces of said bearing members, and means for maintaining the entire series of bearing elements submerged in 55 lubricating medium under hydrostatic pressure whereby the wedge-like films created on rotation of the spindle will react thereagainst to maintain the spindle against both radial and axial displacements under varying loads, substantially 60 as and for the purpose described. 65

3. In precision high speed spindle construction, the combination with a housing member having spaced bearing receiving recesses of a spindle extending transversely of the housing and into said 70 75

5 recesses, said spindle having a reduced bearing portion alignable with each of the recesses, at least one of said reduced portions having a pair of oppositely disposed frustro-conical zones, a plurality of oscillatable bearing elements arranged in each of the bearing recesses in circumscribing relation to the included bearing portion of the spindle, said bearing members having an oscillatable non-translatable outer connection
 10 with the housing and having their respective inner faces shaped to conform to the adjacent included bearing portion of the spindle, and means for maintaining the housing and bearing chambers filled with lubricant under appreciable hydrostatic pressure whereby on rotation of the spindle interposed wedge-like films will be created between the respective bearing members and the spindle, steadyng the same at spaced points against radial displacement of the axis of rotation thereof under varying load conditions and simultaneously reacting on the tapered zones thereof to prevent longitudinal displacement of the spindle.

4. The combination with a rotary spindle having opposed tapered zones providing frustro-conical bearing portions, of a precision mount therefor including a support having a recess adapted to circumscribe the zones in spaced relation thereto, bearing members interposed between the support and spindle disposed in a series circumscribing the bearing portion of the spindle, each of said bearing members having oppositely inclined tapered segmental recesses formed in the inner faces thereof in conforming relation to the zones on the spindle, means mounting said members for oscillatory, non-translatable movement with respect to the support, and means for main-

5 taining said bearing portion of the spindle and circumscribing shoes submerged in lubricant under appreciable hydrostatic pressure whereby a continuous oil film of homogeneous character is produced between all of said bearing members and the bearing portions of the spindle restraining the latter against radial and translatory displacement under varying loaded conditions.

5. A bearing structure of the character described for prevention of radial and longitudinal displacements of a precision spindle under varying load conditions, including a spindle having opposed spaced frustro-conical bearing portions, and a plurality of bearing shoes arranged in circumscribing relation with respect to said portion of the spindle, a supporting member providing a chamber circumscribing said spindle portion and shoes, means mounting said shoes for individual oscillation in a plane transversely of the axis of the spindle, each of said shoes having spaced frustro-conical segments on its inner face substantially conforming to the shape of the spindle for interfitting engagement therewith, the spacing of said portions providing an intervening lubricant receiving groove, and means maintaining the bearing receiving chamber completely filled with lubricant under hydrostatic pressure whereby on rotation of the spindle wedge-like films will be produced between the bearing member and spindle reacting on the spindle in a direction at an angle to the axis thereof whereby jointly to restrain the same against both radial and longitudinal displacements under varying loads.
